UNITED STATES PATENT OFFICE.

THOMAS H. McCRAY, OF TYRONE, ARKANSAS.

STEAM-PLOW.

SPECIFICATION forming part of Letters Patent No. 226,921, dated April 27, 1880.

Application filed March 16, 1880. (No model.)

To all whom it may concern:

Be it known that I, THOMAS H. McCRAY, of Tyrone, in the county of Cross and State of Arkansas, have invented certain Improvements in Steam Rotary Plows, of which the following is a specification:

This invention relates to certain improvements in steam-plows; and it consists in the general construction of the whole machine; also, in the form of the plow teeth or points, in the combination of the apparatus for raising and lowering the plow-cylinder, and the means whereby the cylinder is sustained in the frame, all of which will be more particularly hereinafter described.

Figure 1 is a side elevation of the machine. Fig. 2 is a plan view. Figs. 3, 4, and 5 are details of the several parts of the plow-cylinder and lifting-levers.

The frame A, which supports the whole apparatus, is usually made of rolled wrought-iron of sufficient width and thickness, having a flange on each edge on the outsides of the frame and put together substantially with iron rods or bolts.

The main shaft B is stationary. The intermediate shaft, C, is also stationary, and they are both turned off, and a piece, a, is bored out and fitted on the ends of said shafts, with flanges extending on either side and bolted to the flanges on the frame A, to serve as bearings or journals for the shafts B and C.

The frame is bent inwardly in front until the two side bars come nearly together at the front end at A', between which a piece of iron or wood, A'', is bolted. They may also be arched upward to allow the front wheels to pass under in making short turns. The other or rear ends of the side frames are turned up, as at A''', to support the shaft b, for hoisting or lowering the plow-cylinder P.

There are two iron bars, a' a'', fastened on the inside, which extend across the bottom of the frame A, on which the water-tank D and the platform D' are supported.

The cylinder P is composed of a number of wheels or centers of the proper diameter, each one being wide enough on the periphery to allow two rows of teeth or plow-points to be fastened in it, and it is made of cast or malleable iron, having slots or holes cast in it for

the insertion of the teeth p. The rims of these wheels must be wide and deep enough to support the said teeth, having a semicircular space, p', on each side thereof, opposite each plow point or tooth, to admit of a set-screw, p'', by which the teeth will be more securely fastened. These wheels or centers are bored out and fitted on and keyed to shaft P', the key-seats being so arranged, if desired, that the wheels may be fastened on the shaft with the plow-points running in spiral or parallel lines with the shaft, and the plow-points must be three or more inches apart. Each wheel is to have two rows of teeth in it, around the same, with from six to thirty rows therein, and the plow-points are to be so arranged that those in every alternate row, as the cylinder revolves, will pass directly in the middle of the space between the teeth in the preceding row, and thus break and pulverize all of the ground.

The levers E, in which the cylinder-shaft is sustained and revolves, are of wrought or malleable iron or of steel, and large enough to admit of the shaft C passing through their ends, and on which shaft C they are hinged, and they have a boss on each side, through which is an orifice for the ends of the cylinder-shaft P'. At the outer ends there are segments F F', with cogs to mesh with the cogs of pinion-wheels F' F'' on the transverse shaft b, supported in upturned part of frame A, by which the segments are raised or lowered, and consequently lifting or lowering the cylinder P, which revolves in the levers E E.

Behind each pinion F' F'' is a beveled wheel, F'' F''', which meshes with a similar wheel, F''' F''', on the ends of the sloping shafts H H, having similar beveled wheels h h at their upper ends, meshing with beveled wheels on the two ends of a transverse shaft, R, supported in brackets sustained by the water-tank D. On this shaft R is a wheel, G, by which the lifting and lowering of the plow-cylinder is regulated.

A curved plate, L, is bolted to the inside of the frame A on each side, opposite to the middle of the levers E E, and is also fastened securely at the top by rods extending from the bearings of the shaft C to the top of the upturned end of frame A. These plates L L are

wide enough to contain a groove, $\frac{1}{2}$ in which the ends of the cylinder-shaft P' can slide. The circle of these plates $L L$ has its center at the shaft C , as also that of the cylinder-shaft, and the circle of the segment-rack on the ends of the levers $E E$. These plates $L L$ will relieve the strain of the cylinder from the shaft C , and by forming a thick boss on the outside of the levers $E E$ the bearings for the cylinder-shaft will be lengthened, and thus increase its durability.

The shape of the plow points or teeth is as follows: From the point where they emerge from the surface of the wheel or center they are set back or bent to an angle of from a twelfth to a sixth of the circumference formed by their extreme outward points, and from four to six inches from the outer end they must be bent forward to an angle of about forty-five degrees, and gradually tapered to a sharp point. The object in bending them backward is to assist in clearing the points of all dirt, trash, &c., and the points are bent forward, that they may enter the ground early. The plow-points are fastened in the wheels or centers by a key on the front edge, which is made secure by a set-screw in the apertures in the wheels, heretofore described. The keys have heads formed on them to be readily removed thereby.

The machine is placed on four wheels, $O O O' O'$, of suitable diameters, and should be wide on the tread to support the heavy weight on soft ground. The main shaft B must be bent to support the boiler M . The engine-cylinders $X X$ are fastened to the upper part of the boiler M . The main driving-wheels $O' O'$ are supplied with hubs that extend outside of the rim, which must be turned off, and the cog-wheels $N N$ bored out and keyed on them.

To the interior of the rim of wheels $O' O'$ are cogs, which mesh with a driving-pinion on the crank-shaft C' , which is operated by the pitmen from the engine-cylinders $X X$ above it. This crank-shaft C' is supported on bars B' , which extend between shafts B and C , and are permanently attached thereto. The pitman of each cylinder is connected to the piston-rod in the usual manner, and the crank-shaft C' is driven from the cylinders $X X$, and the driving-pinions on the ends of crank-shaft C' mesh with the cogs inside of the rim of the driving-wheels $O' O'$ and propel them forward. The cog spur-wheels $N N$, which are fixed on the hubs of wheels $O' O'$ and revolve with them, work into the pinions $c c$ on shaft C . There are also

cog-wheels C'' on shaft C , which mesh with pinions $c'' c''$ on the ends of shaft P' of the plow-cylinder. When motion is communicated to the crank-shaft C' , and the frame is moved ahead at the same time by the train of wheels just described above, rapid motion is communicated to the plow-cylinder, and the ground thoroughly pulverized by the rotary action of the teeth or plow-points, and the depth to which they are to be driven is governed by the apparatus consisting of the shaft R , supported on the water-tank, the beveled gearing at its two ends operating upon the inclined shafts $H H$, which operate by beveled gearing at their lower ends upon the transverse shaft b , on which are pinions $F' F'$, which operate upon the segment-racks F on the ends of the levers $E E$, which sustain the shaft of the plow-cylinder P . These movements are under the control of the driver by means of a hand-wheel, G . Near his hand is also another hand-wheel, R' , which is on the top of a vertical rod, r' , at the bottom of which is a cogged wheel, r'' , which works in a segment-rack on the inner end of the frame, on which is the axle of the front wheels, $O O$, so that the driver can control the direction of the forward wheels for steering the plow in any direction.

I claim—

1. The steam rotary plowing-machine consisting of the frame A , the driving and gear wheels, whereby the plow-cylinder is rotated, the means for operating the levers $E E$, which sustain the plow-cylinder, consisting of the transverse shafts R and b , with their beveled gears, the side shafts, $H H$, the pinions $F' F'$, and segments $F F$, all combined substantially as and for the purpose described.

2. The teeth or plow-points bent backward from the centers, and having their points hooked, substantially as shown, and for the purpose described.

3. The levers $E E$, pivoted on the shaft C , having at their ends segment-racks F , in combination with the cylinder P and pinion F' , as shown and described.

4. The combination of the shafts $R H H b$, with their connecting beveled gears, the pinions $F' F'$, and segment-racks $F F$, guide-plates $L L$, and cylinder P , substantially as and for the purpose described.
